(57) **CLAIM**

The ornamental design for a breakout for cable assembly, as shown and described.

DESCRIPTION

FIG. 1 is rear and left side perspective view of a breakout for cable assembly, showing my new design;

FIG. 2 is a front and right side perspective view thereof;

FIG. 3 is rear and right side perspective view thereof;

FIG. 4 is a front and left side perspective view thereof;

FIG. 5 is a top plan view thereof;

FIG. 6 is a rear elevation view thereof;

FIG. 7 is a side elevation view thereof; and,

FIG. 8 is a front elevation view thereof.

The broken line showing of the environment is for illustrative purposes only and forms no part of the claimed design.
